METAL STORM WINDOW

Harry R. Sugar, Akron, Ohio

Application July 26, 1950, Serial No. 176,045

4 Claims. (Cl. 20—55)

1

This invention relates to a new metal storm window and more particularly to a window with extruded stiles and a channel in the outer surface of each stile containing an extender which is preferably pressed by a spring against the wall of the opening into which the window fits.

The elements forming the frame and the top, bottom, and middle rails of the sashes are of uniform dimensions throughout their length except where portions may be cut away. They are preferably formed by the extrusion of a metal or plastic. A light-weight aluminum alloy is the preferred construction material. These elements may be cut to length from the extruded strips either at the plant where the extruded strips are formed or at scattered assembly plants. Any uncut strip of any of this stock may be used for any sized window. The frame will preferably be assembled with the stiles an inch or two longer than required. At the house or other place of installation these stiles are readily cut to length; the window is put in place with the top of the window flush with the top of the casing or other opening to which the window is to be fitted. The extenders are then adjusted to fill in the opening.

The stiles may be made of two extruded parts. The top and bottom portions of each stile are of different cross section. They may be separately formed, each of the desired cross section, and then joined as by welding. As an alternative method, a single piece of uniform cross section from the top to the bottom, the length of the stile, may be employed; and a separate element of uniform cross section may be united to its bottom portion to convert this to the desired cross-sectional configuration. Whatever the method of construction, there is a channel in the bottom half of each stile in which the lower sash slides. This is located toward the inside face of the frame. The inner wall of the channel is cut away toward its top to facilitate the insertion and removal of the lower sash. On the upper portion of that wall of each stile which faces the sashes, toward the outside face of the frame, there is a vertical ledge or rest which extends substantially the whole of the upper half of the stile. It prevents the upper sash from falling out and forms a weather seal with the outer face of the upper sash.

The invention will be further described in connection with the accompanying drawings in which—

Fig. 1 is an elevation of the inside face of the window;

Fig. 2 is an enlarged section on the line 2—2 of Fig. 1;

2

Fig. 3 is an enlarged section on the line 3—3 of Fig. 1;

Fig. 4 is a plan view of the upper right corner of the window;

5 Fig. 5 is an enlarged prospective view taken at the intersection of the two portions of a stile;

Fig. 6 is an enlarged detail showing a portion of a window with the extender forced outwardly by a spring;

10 Fig. 7 is a section on the line 7—7 of Fig. 6;

Fig. 8 is a section on the line 8—8 of Fig. 7; and

Fig. 9 is a section through an alternative stile construction.

The window frame is composed of the top 1, the 15 stiles 2 and 3, and the bottom panel 4, a relatively immobile upper sash 5, and the lower sash 6 which may be moved vertically. The sashes are not fastened in the frame and may be easily removed.

20 In a preferred form of the invention each stile of the frame is composed of two extruded elements welded together. Fig. 5 shows the weld line 12 between the upper element 13 and the lower element 14. These two elements are of

25 different cross section, and the end 15 of a wing portion 16 of the lower element serves as a rest for the upper sash on each side of the window. The two stiles are identical, and the same reference numeral is used to indicate identical parts.

30 Fig. 4 shows a plan view of the top corner of the window, and this illustrates the shape of the cross section of the upper part 13 of the stile 3. The cross section is in the shape of a small letter h, which in Fig. 4 is shown backward but

35 which would be shown frontward in a corresponding view of the stile 2. It would also be shown frontward if viewed from the bottom. The width of the stile is measured by the length of the element 20 (Fig. 4) of the element 13. This is the vertical portion of the small letter h. The hump of the h is composed of the part 21 which forms the face of the stile which faces the sashes and the part 22 which forms the inside face of the stile. The portion of the element 20 which projects inwardly from the face 21 forms a vertical rest for the upper sash and prevents the rain, 40 snow, and wind from entering along the edges of the upper sash.

The channel formed by the parts 21 and 22 and the lower part of the element 20 houses extender 25. This extender is U-shaped, more or less, and is of sufficiently thin material to be springy and

45 is to be sprung into place in the channel. The inner portion of the extender is preferably corrugated, as indicated at 26, to grip the inner surface of the channel so that the extender retains

50

55

The channel formed by the parts 21 and 22 and the lower part of the element 20 houses extender 25. This extender is U-shaped, more or less, and is of sufficiently thin material to be springy and is to be sprung into place in the channel. The inner portion of the extender is preferably corrugated, as indicated at 26, to grip the inner surface of the channel so that the extender retains

any location in which it is set. In alternative arrangements explained in connection with Figs. 6-9, the extenders in the stiles may be held in place by springs.

Fig. 3 is a section of the lower portion of the stile 3. The back member 30 is equal in length and width to the member 20 of the upper portion of the stile. The channel formed by the parts 31, 32, and a portion of the part 33 (which is equal in length to the part 30) is equal in depth to the inner portion of the element 20 so that the part 32 coincides exactly with the part 21. The front wall 33 of the lower element of the stile coincides exactly with the front wall 22 of the upper element of the stile. The wing 16 is thus formed by the parts 30, 34, and 31. It is the upper edge of this wing which forms the rest 15 (Fig. 5) for the bottom of the upper sash.

The extender shown in Fig. 3 is the same extender as shown in Fig. 6. The parts of the upper and lower portions of the stile coincide to form a channel on the lateral face of the frame, which extends from the top of the stile to its bottom, and the extender 25 is of substantially the same length as the stile and fits into this channel.

The space between the wing 16 and the front wall 33 of each stile—i. e., the space bounded by the portions 31, 32, and 33 of the lower portion of the stile—forms a channel 38 in which the lower sash is vertically movable.

Fig. 2 illustrates how the pane in the lower sash 6 rests on its bottom rail. This rail is an extruded element and comprises, in addition to the channel 40 in which the lower sash rests, a lip 41 which forms a handle for vertical movement of the lower sash, a groove 42 in the underside of the rail between the lip 41 and the channel 40 (the purpose of which will be explained immediately), and a depending lip 43 on the outside of the window. The lip 43 is close over the outside of the joint between the lower sash and the bottom panel 4 of the frame and helps to keep the rain and wind, etc., from penetrating the joint. The channel 40 is made up of the outside and inside walls 44 and 45 and the bottom 46. This channel 40 is lined with felt or the like to receive the bottom of the lower pane of glass. The ends 46 of this bottom rail advantageously extend into the channels 38 on opposite sides of the stiles. To form the projecting ends 46 of the channel, it is necessary to remove the ends of the lip 41 and the depending portion 43 and narrow the bottom portion 46 to a width not substantially greater than the width of the channel 40. The ends 46 should fit into the channels 38 with sufficient play to permit unhindered vertical movement of the lower sash.

The opposite edges of the panel 4 fit into the channels 38 on opposite sides of the frame. To accomplish this, the ends of the tongue 50 which extends up into the groove 42 to form a weather-proof seal, must be removed. This bottom panel 4, as shown, is channel shaped and accommodates the narrow extender 53. The whole, or at least the upper portion of the extender 53 is corrugated, as indicated, so that it remains indefinitely at any adjustment. The panel 4 is riveted in place in the channels 38 by rivets 54 (Fig. 1), and the adjuster fits within these rivets.

The top 1 of the frame is composed of the top portion 60, the outside wall 61, the inside wall 62, the bottom wall 63, and the stop 64. This provides an opening 65 for the top of the upper sash 5. The edges of the opening 65 are advantageously beveled, as indicated. Clips 67 are pro-

vided to press the upper sash against the outer wall 61 of the top and prevent rattling. By making the top wider than the stiles, by the width of the inner wall 62 of the top, and by cutting away unwanted portions of the top, and making the inside wall 62 somewhat longer than the other portions, the ends of the wall 62 fit against the inner face of the stile and are held in place by rivets 69.

10 The upper rail 70 of the lower sash and the bottom rail 71 of the upper sash (sometimes called meeting rails) are of extruded material. The outer wall 72 of the rail 70 and the inner wall 73 of the rail 71 are both beveled upwardly outward. As the two rails come together, the two sashes are spread: the upper sash is pressed against the element 20 and the bottom sash against the wall 33 of the channel 38. As a result there is a tight union between the two rails 15 which prevents any rattling of the sashes and keeps out the weather. The rail 71 rests on the stops 15 (Fig. 5).

As indicated, the top and two sides of the upper pane and the two sides of the lower pane are 25 embraced by thin metal channels 75 for protection. These channels may be extruded but are preferably bent from sheet material and simply clipped or sprung in place.

To assemble the window, the sash 5 is first put 30 in place. The upper end of this sash is slipped into the opening 65 in the top 1 behind the springs 67 and is brought to rest on the stop 15. There is a little play between the top of the sash 6 and the stop 64 (Fig. 2) which permits lifting 35 the sash a little above the stop 15 in bringing it to rest in that position. The lower sash 6 is then slid in place in the channels 38 behind the front walls 33 of the lower portions of the stiles. Figs. 1 and 5 show how the front wall 33 of each stile 40 is cut away a little below the middle rails down to the edges 71 to permit tilting of the upper portion of the lower sash 6 inward as the sash is lowered in place, and when it is removed. As the sash is lowered, it is brought into the up-right position; and as it comes to rest on the bottom panel 4, the wall 72 of the middle rail 70 of the lower sash slides against the wall 73 of the middle rail 71 of the upper sash so that the upper sash is pushed outwardly against the inwardly 50 protruding portion 20 of the upper portion of each stile, and the lower sash is pushed inwardly against the front wall of the channel 38. The beveled surfaces may be stepped in a complementary manner to form a tighter seal, if desired.

55 Instead of forming the stiles of the frame of two parts welded at the middle, they may be formed of two parts which are fitted together with a tongue and groove. This is illustrated in Fig. 7. Each stile is formed from top to bottom of the h-shaped extruded element 103 which contains the groove 104 which, likewise, runs from the top to the bottom of the stile. The element 105, which is provided with a tongue 106 which fits into the groove 104, is only the height of the lower sash and is slid into place in the lower part of the groove 104. Preferably, there is a notch 107 in the back wall of the stile to receive the backwardly projecting arm 108 of the element 105. When this type of construction is used, the upper sash rests on the arm 108 and the adjoining wall 109. The top portion of the front wall 110 of the element 105 is cut away, just as in the form of the invention just described the front 70 wall is cut away to the edge 71 (Figs. 1 and 5).

The extenders are advantageously spring pressed by springs preferably located in the channels at the top of the frame and at opposite ends of the bottom panel 4. Figs. 6-8 illustrate how these springs 111 may be fastened in the channels. The overhanging lip 112 and vertical lip 113 are extruded into the bottom of the channel and extend the whole length of the channel. There are two notches 114 in one side of the leaf spring 111 which permit it to be slipped around the lip 112. After the spring has been thus fitted over this lip, the other lip 113 is bent down at 115 over the portion of the spring which lies in the bottom of the channel under the lip 112. Fig. 7 shows the relation of the parts before the lip 113 is bent, and Fig. 8 shows how a portion of the lip 113 is bent over to hold the spring in place. Other means for holding the spring in place may be used.

Fig. 9 shows an alternative type of spring assembly. The view shown in Fig. 9 is similar to the view shown in Fig. 4 except that it is a cross section through the stile instead of showing the top of the stile and a part of the top rail. The outer rest 220 for the lower sash 206 corresponds with the element 20 of Fig. 4. The cross element is identified by the reference numeral 221 and the inner element by the reference numeral 222. These elements correspond to the elements 21 and 22 of Fig. 4. The extender 225 need not have its ends corrugated. Corrugation is desirable where there is no spring (Fig. 3) and may be used with a spring (Fig. 7) but is not necessary.

In the bottom of the channel shown in Fig. 9 two lips 213 are extruded. The spring 211 which may be the same shape as the spring 111 (Fig. 6) is placed between these two lips and then with any suitable element the lips are bent over onto the spring as indicated in dotted lines. This holds the spring in place. The spring keeps the extender 225 extended against the wall of the opening in which the window is placed.

In fitting the window into place, the size of the opening for the frame is approximated. Exact measurement is not necessary, and it is not necessary to measure the angles at the various corners of the opening. Oftentimes the angles vary from 90 degrees. With the storm window of this invention any small variation in the angles, due to sagging of the house, etc., is taken care of by the extenders. The measurements will ordinarily be sent to an assembly plant located in the general neighborhood of the installation. If preferred, the various parts may be cut to size at the factory and shipped to the assembly plant after the fashioning is completed. The stiles will be cut to length but will generally be made an inch or two longer than it is considered will be required. The top and bottom panel of the frame are then cut to length; the portions of the top which must necessarily be removed and the end portions of the bottom panel which must be removed are then preferably sawed away. They may be removed by abrasion or other means if desired. The middle rails of the sashes which may both be cut from the same piece are then cut to length. They extend from one stile to the other. The bottom rail of the sash is cut to the required length. If the ends 46 are to be narrowed to fit in the channels 38, the bottom and middle rails may be about the same length.

The panes are cut to size. The channels 75 are cut to length and snapped over the sashes.

The middle rails 70 and 71 are placed over the

panes of the lower and upper sashes and are held in place by suitable packing. The lower sash is fitted into the channel 48 of the bottom rail with felt or other packing to hold it in place. The front walls of the channels 38 of each stile are cut away to the edges 77 to aid in the insertion and removal of the lower sash. The top rail 1 and bottom panel 4 are then riveted in place in the stiles.

10 The window is now taken from the assembly plant to the place of installation. The exact measurement from the top to the bottom on each side of the opening is made, and the stiles are cut to length. One stile may be somewhat longer than the other. The frame is then put in place, and the side extenders 25 and the bottom extender 53 are pulled out (or sprung out) to meet the edges and bottom of the opening. The extenders need not stick out uniformly along the edges of the frame but only to the extent required to make a tight fit with the edges of the opening. The window will then be secured in place as by nails. Nails having a head located on one side of the shank may be used and driven into the window frame alongside the extenders with their heads bearing down on the extenders. Where desired, calking may be inserted between the extenders or the top of the frame and the walls of the opening. In this manner a substantially airtight and 20 weather-tight seal is made around the storm-window frame. The upper sash is then put in place and then the lower sash. The window is then completed and ready for use. In the summertime the sashes may be removed, and if desired, screens may be inserted.

25 Felt for insulation and for muffling the noise may be applied to various surfaces, as desired. For instance, the rest 20 for the upper frame may be covered with felt, and felt may be used 30 in the channel 38.

35 Fig. 1 shows a type of ventilator 120 which may be used with the window of this invention. It is formed of a rod 121 fastened at both ends to the stile 2. Leaves 122 are supported on the 40 rod 121 in such a way that they may be swung horizontally to one side of the rod or the other, to provide a rest for the sash at any desired level. When a selected leaf is swung toward the open window, and the window is then lowered, the lip 41 rests on the leaf. The ventilator may be of any desired length and formed with any 45 desired number of leaves.

50 The invention is not limited to the exact arrangement and details disclosed and described. Neither is it limited to a structure which includes all the novel features described. It is defined in the appended claims.

55 This application is a continuation in part of my applications Serial No. 594,296, filed May 17, 1945, and Serial No. 629,547, filed November 19, 60 1945.

What I claim is:

65 1. A storm window with extruded stiles each of which has in its outer face a channel with at least one lip extruded in the bottom thereof, an extender movable in and out of the channel, and a leaf spring shaped and positioned to press against the extender, one side of the central portion of the spring being against the base of the 70 lip with a portion of the lip bent thereover.

75 2. A metal storm window frame each stile of which has a channel in that surface which is adapted to face one side of the opening in which the frame is to be located, and extending in a straight line longitudinally of the bottom of the

channel and uniformly spaced from both walls thereof a lip adapted to be bent over at any location throughout the length thereof at which the central portion of a leaf spring is placed with the ends of the spring spaced from the bottom of the channel.

3. An extruded stile for a storm window frame which has a channel in that surface thereof which is adapted to face the side of the opening in which the frame is to be located, and extending lengthwise throughout the bottom of the channel and uniformly spaced from the walls thereof a lip which is adapted to be bent over at any place between the ends thereof to hold the central portion of a leaf spring with the ends of the spring spaced from the bottom of the channel.

4. The method of assembling a storm window frame formed with a stile having a channel in that surface thereof which is adapted to face one side of the opening in which the window is to be located, with a lip extending lengthwise through the bottom of the channel and uniformly spaced from the walls thereof, which method comprises placing one edge of the central portion of a leaf

spring against the base of the lip intermediate the ends of the lip with the ends of the spring spaced from the bottom of the channel, and then bending the lip thereover to hold the spring in position in the channel.
